US00D388851S

United States Patent

[19]

Rollinson et al.

[11] Patent Number: Des. 388,851

[45] Date of Patent: ***Jan. 6, 1998

[54] **GOLF PUTTER HEAD WITH RECESSED AND FLUTED REAR SIDE AND STEPPED TOP WALL**

[75] Inventors: **Augustin W. Rollinson; Richard C. Helmstetter**, both of Carlsbad, Calif.

[73] Assignee: **Callaway Golf Company**, Carlsbad, Calif.

[*] Notice: The portion of the term of this patent subsequent to Nov. 4, 2011, has been disclaimed.

[**] Term: **14 Years**

[21] Appl. No.: **47,834**

[22] Filed: **Jan. 16, 1996**

[51] LOC (6) Cl. **21-02**

[52] U.S. Cl. **D21/217**

[58] Field of Search **D21/217-219; 473/340, 341, 251-256**

[57] **CLAIM**

The ornamental design for golf putter head with recessed and fluted rear side and stepped top wall, as shown and described.

DESCRIPTION

FIG. 1 is a perspective view of a golf putter head with recessed and fluted rear side and stepped top wall embodying our new design;

FIG. 2 is a top plan view thereof;

FIG. 3 is a rear view thereof;

FIG. 4 is a front view thereof;

FIG. 5 is a bottom plan view thereof;

FIG. 6 is a toe end view thereof; and,

FIG. 7 is a heel end view thereof.
